UNITED STATES PATENT OFFICE.

JAMES H. BAKER, OF ALLEGHENY, PENNSYLVANIA.

DESIGN FOR A CHANNEL-IRON.

SPECIFICATION forming part of Design No. 28,864, dated June 14, 1898.

Application filed October 30, 1897. Serial No. 656,968. Term of patent 14 years.

To all whom it may concern:

Be it known that I, JAMES H. BAKER, a citizen of the United States, residing at Allegheny, in the county of Allegheny and State of Pennsylvania, have invented and produced a new and original Design for a Channel-Iron, of which the following is a specification.

In the accompanying drawing, which makes part of this specification, the figure is an isometrical perspective of a channel-iron for railroad-couplings.

In the view presented, A A are flanges extending longitudinally along the edges of the channel-iron. B is the web uniting said flanges. Said flanges A A are duplicates of each other and are curved in cross-section on

their upper surfaces a a upon a radius substantially the same as the curve b b, which unites the inner edges of said flanges with the web B.

The lower outer corners of the channel-iron are rounded, as shown at b' b'.

Having described my invention, I claim—

The design for a channel-iron for railroad-coupling substantially as shown and described.

In testimony whereof I have hereunto set my hand this 22d day of October, A. D. 1897.

JAMES H. BAKER.
